UNITED STATES PATENT OFFICE.

NEIL ROSS, OF NEW YORK, N. Y.

DESIGN FOR A GAME-BOARD.

SPECIFICATION forming part of Design No. 32,138, dated January 23, 1900.

Application filed December 20, 1899. Serial No. 741,065. Term of patent 3½ years.

To all whom it may concern:

Be it known that I, NEIL ROSS, a citizen of the United States, and a resident of the city of New York, borough of Manhattan, in the 5 county and State of New York, have invented and produced a new and original Design for a Game-Board, of which the following is a full, clear, and exact description.

Reference is to be had to the accompanying 10 drawing, forming a part of this specification, in which the figure is a plan view of a game-board, showing my design.

The leading feature of the design for a 15 game-board consists in a number of connected squares on a rectangular base, certain of the squares presenting various clouded effects alternating with contrasting squares.

A minor feature of the design consists in the border-panels and the square corner-panels, both having a clouded effect.

Having thus fully described my invention, I claim as new and desire to secure by Letters Patent—

The design for a game-board, as herein shown and described.

In testimony whereof I have signed my name to this specification in the presence of two subscribing witnesses.

NEIL ROSS.
